UNITED STATES PATENT OFFICE.

TONY J. PATT, OF CHICAGO, ILLINOIS.

APPARATUS FOR ACROBATS.

Application filed September 10, 1921. Serial No. 499,761.

To all whom it may concern:

Be it known that I, TONY J. PATT, a citizen of the United States, residing at Chicago, in the county of Cook and State of Illinois, have invented certain new and useful Improvements in Apparatus for Acrobats, of which the following is a specification.

This invention relates to apparatus for acrobats' use and has for its object producing a particular effect or trick when used for acrobatic purposes. The principal operation with the apparatus consists of the principal performer, while suspended by his toes, supporting by means of his teeth an assistant who is thus suspended horizontally by her belt, and as the assistant is rotated in one direction by the principal performer the principal is rotated in the opposite direction by the apparatus as both performers move downwardly.

Of the accompanying drawings Fig. 1 is an elevation more or less diagrammatic of the apparatus which embodies the features of my invention; Fig. 2 is an enlarged elevation mainly in section, of the lower portion of the principal apparatus shown in Fig. 1; Fig. 3 is an enlarged sectional elevation of the upper portion of the principal apparatus at 90° to Figs. 1 and 2; Fig. 4 is an enlarged detail view of a plunger of the apparatus; and Fig. 5 is an enlarged sectional view along the line 5—5 of Fig. 1.

The apparatus in general consists of a tube 5 which supports, in a manner herein-after described, fork pieces 6 to which the principal performer hangs by his toes and heels when performing the trick. The upper end of the tube 5 is supported by means of a ring 7 and a cable 8 and various guy-cables 9, the ring 7 being connected to the tube 5 by a pulley frame 40. A crosspiece 10, fixed to the upper end of the tube 5, encloses the lower guy-cables 9 and prevents at all times rotation of the tube 5. A carrier 11 is mounted on rollers 12 on one of the guy-cables 9 and supports a seat 13 in which the assistant performer sits as she is pulled upwardly by means of a rope 14, fixed to the carrier 11 and passing upwardly through the crosspiece 10 and between pulleys 15 to any suitable elevating apparatus.

When the trick is being performed the principal performer, by any suitable means, suspends himself on the fork 6 by his toes

and heels, and the assistant is then drawn upward on the carrier until she is within reach of the principal. She is provided with a belt and a suitable swiveled strap attached thereto, and the principal, by means of this belt and strap, lifts the assistant from the seat and suspends her horizontally by clasping the free end of the strap between his teeth. The principal performer then, with the assistant suspended horizontally, rotates the assistant on the strap as an axis, and, while she is thus rotating in one direction, both performers, by means of the apparatus hereinafter described, are lowered and at the same time the principal performer is rotated in the opposite direction, thus causing the assistant to be rotated horizontally in one direction and the principal to be rotated vertically in the opposite direction.

The apparatus, by means of which the performers are lowered, and the principal performer is rotated, comprises a tube 16 slidably mounted in the tube 5, and supporting on its lower end, the fork 6 upon which is to be suspended the principal performer. The tube 16 has a spiral flange 17 extending from one end to the other and encircling the tube 16 as many times as may be desired. Fixed to the lower end of the tube 5 is a collar 18 through which the tube 16 passes, and in this there is a spiral groove 19 through which passes the spiral flange 17. By means hereinafter described the tube 16, supporting the performers, is allowed to move downwardly and in doing so it is rotated by means of the spiral flange 17 passing along the groove 19, it being understood that the collar 18, in which the groove 19 is formed, is held stationary by means of the tube 5 and the cross-bar 10 fixed thereto; the tube 5 being at all times held stationary by this cross-bar and the suspending cables.

In order to hold the tube 16 stationary in its proper place in the tube 5, before it is desired to descend, I provide in the lower end of the tube 5 a slot 20 into which projects a pin 21 which is slidably mounted on a collar 55 fixed to the lower end of the tube 16. The pin 21 is normally held resiliently upward by means of a spring 22. When this pin is in the slot 20 rotation of the tube 16 is prevented, and hence the flange 17 and slot 19 will prevent the tube 16 from passing downwardly. But, while the opera-

tor is suspended by his toes and heels in the fork 6, he is in a position to press upwardly on one or both of the arms 23, and this will force downwardly the pin 21 out of the slot 20 by means of levers 24 pivoted in their central portions to the lower end of the tube 16. One end of each of these levers is fixed to the rod 23, and each of the other ends is pivoted, by means of links 25, to a rod 26 fixed to the pin 21. By this arrangement, when the rod 23 is pushed upwardly, the pin 21 will be forced downwardly out of the slot 20, and the tube 16 will sink and rotate, carrying with it the performers.

In order to prevent the tube 16 from sinking too rapidly I provide within the tube a plunger 27 which is fixed to the lower end of a rod 28, the upper end of the rod 28 being fixed by means of a bolt 29 and a bracket 30 to the upper end of the tube 5. The tube 16 is closed at its lower end and is filled with some suitable liquid such as oil. A packing box 31 prevents leakage of the oil at the upper end as the tube 16 rotates and passes downwardly. When the trick is to be performed the plunger 27 is in the lower end of the tube 16 and the oil contained in the tube 16 will be substantially all above the plunger. The plunger 27 is hollow but has openings 32 at its lower end and an opening 33 at its upper end. The opening 33 is normally closed by a valve 34 which is slidably mounted on the rod 28 and is forced down against the plunger 27 by the oil when the tube 16 is about to sink, thus closing the opening 33 and forcing the oil to pass through an adjustable opening 35 in the valve 34.

By a consideration of this apparatus it will be seen that, when the pin 21 is released by the performer from the slot 20, the tube 16 will be forced downwardly by the performer's weight, and the performers, with the tube 16, will move slowly downwardly as the plunger 27 passes upwardly through the oil which passes through the opening 35 of the valve. The rate at which the performers move downwardly depends upon the size of the opening 35 which may be adjusted by a screw-valve 36. When the tube 16 is pulled upwardly in the tube 5, in the manner hereinafter described, the valve 34 is forced away from the upper end of the plunger 27, and the oil passes freely around the valve, as its diameter is somewhat less than the inner diameter of the tube 16.

In order to again telescope the tubes 5 and 16 to repeat the trick, I provide a strap 37, the upper end of which is fixed to an elevating cable 38 which passes between pulleys 39 in the frame 40. The upper end of the strap is also fixed to a ball bearing swivel 41, and the lower end is fixed to a flanged collar 42 rotatably mounted on the

upper end of the tube 16. In order to prevent rotation of collar 42 and thus twisting of the cable 38, as the tube 16 sinks and rotates, I provide a slot 43 in the flange of the collar 42 and mount in the tube 5 a rod 44 extending substantially the full length of the tube 5 and fixed thereto. This rod prevents rotation of the collar 42 and hence prevents twisting of the cable 38. The ball bearing swivel 41 is provided so as to reduce the force required to pull the tube 16 upwardly as it rotates. The inner portion of the ball bearing is fixed to the tube 16 by means of the packing-box 31.

The crosspiece 10 comprises main bars 46 which are fixed to the tube 5 by means of brackets 47 which are fixed to a split collar 48. The two members of the collar 48 are fixed to the tube 5 by means of the bolt 29, and bolts 49 press the members firmly against the tube 5. Collars 50 separate the outer ends of the bars 46, and the guy-cables pass between the outer ends of the bars and the collars 50. An additional passageway for cables is formed on each end of the crosspiece 10 by means of straps 51 and collars 52. The two ends of the crosspiece are substantially similar.

While I have described with much particularity many of the details of the apparatus by means of which the trick may be performed, it is to be understood that modification in the apparatus may be made by those familiar with the art without departing from the spirit of my invention as disclosed by the following claims.

I claim as my invention:

1. A trick apparatus comprising means for suspending a performer, means for lowering the suspending means, and means operated by the said lowering means for rotating the suspending means around a vertical axis, said lowering and rotating means coacting to produce rotation of the performer continuously proportional to the lowering thereof.

2. Acrobatic apparatus comprising means for suspending a performer by his feet, means for lowering said performer, means for rotating said performer around a vertical axis, and means fixed to said suspending means and operable by the feet of said performer for setting in motion said lowering and rotating means.

3. Acrobatic apparatus comprising means for suspending a performer by his feet and for lowering and rotating said performer, said means comprising a stationary vertical outer tube, an inner tube rotatably and slidably mounted in said outer tube, suspending means fixed to the lower end of said inner tube, and means for rotating said inner tube as it is forced downwardly by the performer.

4. Trick apparatus comprising a vertically suspended stationary tube, an inner

5 tube slidably mounted in said stationary tube, means for retarding the downward movement of said inner tube when otherwise free to move downwardly, said means comprising a plunger in said inner tube, and means connecting said plunger with the upper end of said stationary tube.

10 5. Trick apparatus comprising a vertically suspended stationary tube, an inner tube slidably mounted in said stationary tube, means for retarding the downward movement of said inner tube when otherwise free to move downwardly, said means comprising a plunger in said inner tube, and means connecting said plunger with the upper end of said stationary tube, said inner tube containing a liquid.

15 6. Trick apparatus comprising a vertically suspended tube, an inner tube slidably and rotatably mounted in said suspended tube, means for rotating said inner tube as it is moved longitudinally in said suspended tube, said means comprising a spiral flange fixed to said inner tube, and said suspended

20 tube having a groove in its lower end into which said flange passes.

7. Trick apparatus comprising a vertically suspended tube, an inner tube slidably and rotatably mounted in said suspended tube, means for rotating said inner tube as it is moved longitudinally in said suspended tube, and a cable fixed to the upper end of said inner tube for pulling the inner tube upwardly.

25 8. Trick apparatus comprising a vertically suspended tube, an inner tube slidably and rotatably mounted in said suspended tube, means for rotating said inner tube as it is moved longitudinally in said suspended tube, a cable fixed to the upper end of said inner tube for pulling the inner tube upwardly, and means for preventing the twisting of said cable when the inner tube is rotating.

30 In testimony whereof, I hereunto set my hand.

40 45 TONY J. PATT.
